UNITED STATES PATENT OFFICE.

GEORGE WETTLAUFER, OF SAGINAW, MICHIGAN.

STACKER.

SPECIFICATION forming part of Letters Patent No. 684,533, dated October 15, 1901.

Application filed April 8, 1901. Serial No. 54,871. (No model.)

To all whom it may concern:

Be it known that I, GEORGE WETTLAUFER, a citizen of the United States, residing at Saginaw, in the county of Saginaw and State of Michigan, have invented certain new and useful Improvements in Stackers; and I do hereby declare the following to be a full, clear, and exact description of the invention, such as will enable others skilled in the art to which it appertains to make and use the same.

This invention is a stacker for threshing-machines; and the improvement consists in certain details in construction of the stacker-pipe by which the objects of my invention are accomplished. These objects are, first, to provide a stacker-pipe made in sections, the outer one of which is adapted to swing horizontally, so that the direction of the discharge in confined spaces, such as the lower floors of barns and storage-sheds, can be varied at will.

Another object is to provide a stacker-pipe with a horizontally-swinging discharge end that will automatically fold back upon the body of the stacker when released and to provide a spring for controlling the force of the swing, together with means for tightly clamping the swinging section to the body of the stacker when in position for discharging.

The construction and operation of the device are illustrated in the accompanying drawings, in which—

Figure 1 shows the stacker in position for discharging. Fig. 2 is a side elevation showing the stacker folded. Fig. 3 is a perspective view of the hinged flanges. Fig. 4 is a side elevation of the stacker-pipe in position for transportation. Fig. 5 shows the manner of reversing the position of the stacker in a small space. Fig. 6 is a part-sectional detail of the clamp.

As is clearly shown in the drawings, the stacker consists in two sections of pipe. The body-section 1 is swiveled to the discharge-chute 2 of the thresher in the usual manner, so that it can be revolved horizontally or elevated to any desired angle. To the outer end of the section 1 is hinged a folding discharge-section 3, adapted to swing in an approximately horizontal plane when the body-section 1 is in position for transportation, as shown in Fig. 4. The object of hinging the

section 3 in this manner is to permit the stacker to be readily placed for discharging into bins or lofts which cannot be reached by the long one-piece stacker in common use. It has been very difficult heretofore to properly direct the straight stacker so as to discharge in the desired position. If a threshing-machine equipped with the ordinary straight stacker made in one piece is drawn into a barn with the stacker in position for transportation, the machine frequently has to be backed out of the barn, turned around, and drawn into the barn again in order to get the stacker-pipe into proper position for discharging. With my improved hinged stacker this inconvenience is avoided. The discharge-section 3 when released readily folds back upon section 1, which in turn can be revolved to any desired position, after which section 3 can be swung back to place and fastened, again forming a continuous pipe, as shown in Fig. 5.

To permit the discharge-section 3 to be handled with greater ease and to fold back upon section 1 automatically when released, I incline the axis of the hinge 4 that connects the two sections so that it makes a small angle with the vertical, as shown in Fig. 3. The section 3 thus has a natural tendency to fold back upon section 1, assuming the position shown in Fig. 2. In order to prevent its swinging with too great force, I provide a spring 5, attached at its ends to both sections of the stacker and extending across the hinge 4, so as to resist the tendency of section 3 to fold back.

In order to prevent the section 3 from dropping or sagging in the event of wear in the bearings of the hinge 4, I have adopted means for readily clamping the two sections together, (shown in Figs. 3 and 6,) in which 6 and 7 are flanged rings hinged together, as above described, and bolted or riveted to the sections 3 and 1, respectively. One of these rings, such as 6, has two upwardly-projecting lugs 8, separated a short distance from each other and connected by a through-bolt 8^a. The ring 7 has two similar lugs 9, between which is pivoted a link 10, slotted at its outer end. An eccentric-disk 10^a is revolvably mounted in this slot, being operated by a handle 10^b.

The two flanges 6 and 7 can be readily clamped together by dropping the link 10 between the lugs 8 and pushing down the handle of the eccentric 10^a, which jams against 5 the bolt 8^a, drawing the flanges 6 and 7 tightly together.

I provide a link 11 on the side of flange 7. This link fastens the rings together at the side of the stacker-pipe.

10 What I claim as my invention, and desire to secure by Letters Patent, is as follows:

1. In a pneumatic stacker, a trunk composed of two sections; a hinge connecting said sections so that the outer section may swing 15 in a horizontal plane when the stacker is in position for transportation; the angle of said hinge being such that the outer section will swing back upon the other section by its own gravity; a cushioning-spring in the rear of said hinge and secured at each end to one section; 20 and clamps secured to the adjacent ends of

the two sections for holding them in operative position, substantially as described.

2. In a pneumatic stacker, a trunk composed of two sections; reinforcing-bands secured to their adjacent ends; a hinge joining said bands at the side of the stacker and so placed that the outer section may swing in a horizontal plane when the stacker is in position for transportation; a hook pivoted to the 25 upper part of one band and adapted to engage a projection on the other band; and a clamp on the side of one band adapted to engage a projection on the side of the other band thereby holding the stacker in operative position. 30

In testimony whereof I affix my signature in presence of two witnesses.

GEORGE WETTLAUFER.

Witnesses:

I. GOULD,
WILLIAM STEPHENS.
